(57) **CLAIM**

The ornamental design for the flip-top sealing cap, as shown and described.

DESCRIPTION

FIG. 1 is a left side view of the closed flip-top sealing cap; and FIG. 2 is a right side view of the closed flip-top sealing cap; and

FIG. 3 is a back view of the closed flip-top sealing cap; and FIG. 4 is a front view of the closed flip-top sealing cap; and FIG. 5 is a top view of the closed flip-top sealing cap; and FIG. 6 is a perspective view of the closed flip-top sealing cap; and,

FIG. 7 is a perspective view of the opened flip-top sealing cap. The dashed lines which indicate an object being sealed by the flip-top sealing cap are included for the purpose of illustrating environmental structure and form no part of the claimed design.
